CLAIM

The ornamental design for a “round identification case,” as shown and described.

DESCRIPTION

FIG. 1 is a front elevational view of an identification case showing my new design;

FIG. 2 is a front elevational view thereof; shown in its environmental use;

FIG. 3 is a rear elevational view thereof;

FIG. 4 is a right side elevational view thereof; the left side elevational view being a mirror image thereof;

FIG. 5 is a top plan view thereof;

FIG. 6 is a bottom plan view thereof;

FIG. 7 is a front elevational view thereof; in an open position;

FIG. 8 is a rear elevational view of FIG. 7; and,

FIG. 9 is a right side elevational view of FIG. 7; the left side elevational view being a mirror image thereof.

The broken line showing a beeper and coin is for illustrative purposes only and forms no part of the claim.
